CLAIM

The ornamental design for an adjustable handlebars for bicycle as shown and described.

DESCRIPTION

FIG. 1 is a top plan view of the adjustable handle bars for bicycle showing my new design;

FIG. 2 is a side elevational view thereof, the opposite side being a mirror image of the side shown herein;

FIG. 3 is a bottom plan view thereof;

FIG. 4 is a cross sectional view thereof taken along line 4-4 in FIG. 3;

FIG. 5 is an end elevational view thereof, the opposite end being a mirror image of the end shown herein;

FIG. 6 is a top plan view thereof with the handle bars in an alternate position; and,

FIG. 7 is a top plan view thereof with the handle bars in another alternate position.

The broken lines in FIGS. 6 and 7 of the drawing are for illustrative purposes only.
